CLOTHING CONTAINER

Abraham Stone, Brooklyn, N. Y.

Application March 21, 1935, Serial No. 12,223

2 Claims. (Cl. 312—144)

This invention relates to storage containers and has particular reference to an improved protective wardrobe cabinet, chest or the like, for the storage of clothing.

5 The invention primarily comprehends a container of the indicated character which is formed of a plurality of interfitting sections which are so constructed that when assembled the sections closely interfit to effectively seal the same against dust, moths and other insects.

10 The invention further contemplates a container composed of interfitting sections constructed of cardboard, corrugated paper board or other light weight inexpensive material, and 15 which have relatively rigid frames of wood or an equivalent material surrounding the junctures of the sections by means of which the relatively flexible sections are prevented from buckling and are caused to closely interfit so as to prevent the 20 ingress of dust, moths or other harmful insects thereto and the egress of insecticide or insect repellent fumes therefrom.

25 The invention further embodies a container composed of a main body section which defines the side walls and a closure, and flanged end sections telescopically fitted over the opposite ends of the body section, which end sections each 30 comprises an end wall provided with integral inwardly directed flanges at each edge thereof, and a marginal frame of wood or an equivalent rigid material secured to and encompassing the outer portion of the flanges adjacent their juncture with the end wall so as to render the outer framed portion of the flanges rigid for effecting a tight 35 fit between the ends of the body section and said outer portions of the flanges, the remaining inner portions of the flanges protruding inwardly beyond the frame and providing free flexible extensions for facilitating the assembly of the sections.

40 The invention also provides a container of the indicated character which is inexpensive to manufacture and may be sold at small cost and which is useful either as a wardrobe cabinet or chest for the storage of wearing apparel.

45 With these and other objects in view, reference is now made to the following specification and accompanying drawing in which there is illustrated an embodiment of the invention, while the appended claims cover variations and modifications thereof which fall within their scope.

In the drawing:

Fig. 1 is a perspective view of a clothing container constructed in accordance with the invention, and illustrating the closure in open position.

Fig. 2 is an enlarged fragmentary vertical sectional view taken approximately on the line 2—2 of Fig. 1 with the closure in closed position.

Fig. 3 is a similar view taken on the line 3—3 of Fig. 2.

Fig. 4 is a perspective view of one of the end sections removed.

The container is illustrated in the present disclosure as a wardrobe cabinet, but obviously the same may rest on the rear wall to serve as a 10 storage chest without departing from the scope of the invention.

Referring to the drawing by characters of reference, the container includes a main body section A and identically formed end sections B 15 and C. The main section A is preferably constructed from a single sheet of cardboard, corrugated paper board or other light weight inexpensive material which is scored and bent on parallel lines to define opposite side walls 10 and 20 11, rear wall 12, closure 13, which is swingably connected to the side wall 11, and a flap 14 provided at the vertical free edge of the closure 13. Constructed in this manner, the body section may be collapsed into a compactly folded condition, in which condition it occupies a minimum amount of space for shipment or for storing the same when not in use.

The side walls 10 and 11 and the rear wall 12 are of equal length, while the closure 13 is of a 30 lesser length, the same being cut away as at 15 at the upper and lower ends thereof. The flap 14 has its opposite end edges 16 converging outwardly from the top and bottom edges 15 of the closure 13 to the longitudinal free edge 17 35 of the flap. The side wall 10 is provided at its free vertical edge with a reenforcing member 18 of wood or other rigid material which is channeled so as to embrace said edge and thereby prevent the wall from buckling and bulging and 40 affording means against which the flap 14 impinges to obtain a tight fit and to prevent the ingress of dust, moths or other insects to the wardrobe or chest when the closure is closed, and the egress of the fumes of insecticides or insect 45 repellents.

The end sections B and C each includes a panel 19 which forms the end walls of the container and each panel is provided with inwardly directed marginal side flanges 20 and 21 and marginal 50 front and rear flanges 22 and 23 respectively, which panel 19 and flanges are preferably formed from a single sheet of cardboard, corrugated paper board or other light weight inexpensive material. The end sections B and C also include a 55

marginal frame 24 of wood or other rigid material secured to and encompassing the outer portions of the flanges adjacent their juncture with the panel 19, the remaining inner portions of said flanges extending inwardly beyond the inner edge of the frame. The frames 24 are preferably formed of strips having their adjacent ends connected together by metallic angle members 25 with fastening elements extending through the ends of the angle members and through the strips of the frame 24 and the flanges of the end sections, as shown so that the said strips may be drawn tightly against the flanges of the end sections. The end sections B and C are designed to telescopically fit over the opposite ends of the main body section A, with the frames 24 surrounding the flanges and the ends of the body section when telescopically interfitting so as to obtain an intimate engagement between the flanges and the walls of the body section for preventing the ingress of dust, moths or other insects to the container and the escape of insecticide or insect repellent fumes.

The flanges 20, 21, 22, and 23 of the end sections are unconnected with each other at their vertical edges whereby the outer portions thereof will intimately fit within the frame 24 and the inner portions of the flanges which protrude beyond the inner edge of the frame provide independent, free, flexible extensions which may be spread apart to permit the wedging of the end sections B and C over the ends of the body section facilitating the assembly of the sections and the obtaining of a tighter interfitting thereof.

In order to provide a clearance and interfitting of the flanges 20 with the reenforcing member 18, the protruding portions thereof, at their forward ends, are cut away as at 26. The front flanges 23 of the end sections each have their protruding inner portions cut away at their opposite ends as at 27 and 28 providing notches to respectively receive the opposite ends of the body section adjacent the juncture of the side wall 11 with the closure 13. The cut away portions 28 provide edges 29 parallel to the inner surface of the reenforcing member from which they are spaced so as to receive and frictionally engage the opposite ends of the flap 17 to insure a tight fit. The protruding inner portions of the front flanges 23 function as abutments or jambs against which the upper and lower ends of the closure 13 engage when the same is closed.

The end sections B and C may be releasably connected with the body section A by any suitable means herein illustrated, as split fastening elements 30 which are engaged through aligned openings in the protruding portions of the rear and side flanges 20, 21, and 22 of the end sections and the rear and side walls 10, 11, and 12 of the body sections.

What is claimed is:

1. A clothing container comprising a main body section constructed of a single sheet of flexible light weight material which is scored to define the side walls and closure of the container, end sections each comprising a panel and integrally formed inwardly directed marginal side, front and rear flanges, constructed of flexible light weight material and a marginal frame of rigid strips of material encompassing the outer portions of the flanges adjacent the juncture of the flanges with the panel and having their adjacent ends connected by metallic angle members with securing means extending through the ends thereof and through the said strips and flanges, said frame surrounding the opposite ends of the body section when telescopically interfitting with the end sections and said flanges providing flexible inner portions extending inwardly beyond the frame, which inner portions may be spread apart to permit of the wedging of the end sections over the opposite ends of the body section, and fastening elements extending through the said inner portions and through the body section for securing the sections together.

2. A clothing container comprising a main body section constructed of a single sheet of flexible light weight material which is scored to define opposite side walls, a rear wall, a closure and a flap hingedly connected to the closure, one of said side walls having a reenforcing member fitted over the free vertical edge thereof and end sections telescopically fitted over the opposite ends of the side and rear walls of the body section, each end section comprising a panel and integrally formed inwardly directed marginal side, front and rear flanges constructed of flexible light weight material, and a marginal frame of rigid strips of material encompassing the outer portions of the flanges of each of the end sections adjacent the juncture of the flanges with the panels thereof and having their adjacent ends connected by metallic angle members with securing means extending through the ends thereof and through the said strips and flanges, said frame surrounding the opposite ends of the body section when telescopically interfitting with the end sections, the remaining inner portions of said flanges extending inwardly beyond the inner edges of the frames and defining flexible extensions which may be spread apart to permit of the wedging of the end sections over the ends of the body section, and said inner portions of the front flange and one of said side flanges of each of said end sections being cut away to provide notches respectively to receive the ends of the body section adjacent the closure and the ends of the said reenforcing member and the flap of said closure.
